LABEL PASTING MACHINE AND THE LIKE

Joseph Ettl, Highlands, N. J., assignor to Pot-
devin Machine Company, Brooklyn, N. Y., a
corporation of New York

Application January 4, 1940, Serial No. 312,353

1 Claim. (Cl. 91—58)

This invention relates to label pasting machines, and has for one of its objects the provision of a machine of this type wherein the stripper fingers are of improved and novel construction whereby wear on the fingers may be readily taken up. My construction also provides for replacement of the fingers when necessary, without entailing the expense of installing a new mount therefor.

In the accompanying drawing:

Fig. 1 is a fragmentary elevational view partly in section of an embodiment of my invention;

Fig. 2 is a plan view thereof;

Fig. 3 shows the stripper finger construction on an enlarged scale; and

Fig. 4 shows a jig or gauge employed for setting the fingers.

Referring to the drawing in detail: 2 designates the paste roller, and 4 the presser rollers of a label pasting machine. The labels are fed across the front of the machine between the paste roller 2 and the presser rollers. I have shown a label at 6 passing through the machine. This is conventional design and will not be discussed in any further detail.

To the rear of the paste or glue roller 2, extending transversely of the machine and mounted in the side frames of the machine is a finger bar 8. This bar carries a plurality of stripper finger or stripper blade holders 10. These blade holders are threaded upon the finger bar, and keyed thereto by key 12, this key preventing rotational movement of the holders relatively to the finger bar and relatively to each other.

Each blade holder is provided with a rectangular aperture 14 for the reception of the shank of the stripper blades or fingers. Each blade holder is also bored to receive a guide bar 16 which passes through the bank of holders.

The stripper blades or fingers are designated 18. These are flat metal plates, each provided with a reduced shank 20, the shanks being inserted into the aperture 14. The blades are held in place in their holders by screws 22.

From the description given thus far, it will be seen that the stripper fingers or blades 18 are individually adjustable in their holders, and that when a blade is worn away so that it is no longer usable it can be replaced without the necessity of replacing the mount also.

For the purpose of setting the blades initially,

and for resetting them from time to time thereafter when they have been worn away to some extent, I provide a jig or gauge 24 on the bed of the machine. This jig is an elongated flat metal strip with a boss 26 at one end which is of the proper size to receive a blade holder 10. The other end of the jig is provided with a boss 28 having a triangular shaped depression 30 in its face. In practice a holder 10 with a blade 18 therein is placed over the boss 26. The blade is then moved in its aperture 14 in the blade holder until the free end of the same fits into the depression 30. The screw 22 of the holder is then tightened to secure the blade to the holder in correct position. Initially all of the blades are set in this fashion, and it will be quite apparent that all of the blades will be correctly set so that their contact with the surface of the glue or paste roller 2 is uniform. As the blades wear away due to their contact with the roller 2, it is merely necessary to remove the holder and blade and reset with the jig. With this arrangement, it is no longer necessary to replace a blade or finger which has been worn, inasmuch as each blade can be reset from time to time until it has been worn away practically up to the shank 20. Not only does this effect a saving in blades so far as the machine owner is concerned, but it ensures accuracy with respect to the contact of the blades with the glue roller, with the assurance that the blades will perform their stripping function in the most efficient manner.

It is to be understood that changes may be made in the details of construction and arrangement of parts hereinabove described without departing from the spirit and scope of my invention.

What I claim is:

In a machine of the class described, a stripper finger bar, a plurality of stripper finger mounts, said bar passing through said mounts and held against rotation relatively thereto, a guide bar passing through said mounts parallel to said finger bar, each of said mounts being provided, above the guide bar, with an aperture, a stripper finger mounted in each aperture, the fingers being individually slideable for adjustment in said aperture transversely of the axis of the guide bar, and a screw passing through the bottom of each mount into engagement with the underside of each finger to hold the latter in adjusted position.

JOSEPH ETTL.
